UNITED STATES PATENT OFFICE.

HORATIO WOODFORD BURTCH, OF CHICAGO, ILLINOIS.

DESIGN FOR WRAPPING-PAPER, &c.

SPECIFICATION forming part of Design No. 20,654, dated March 31, 1891.

Application filed December 9, 1890. Serial No. 374,114. Term of patent 14 years.

To all whom it may concern:

Be it known that I, HORATIO WOODFORD BURTCH, a citizen of the United States, residing at Chicago, in the county of Cook and State 5 of Illinois, have invented and produced a new and original Design for Wrapping-Paper and Paper Bags, of which the following is a specification.

As shown in the accompanying engraving, 10 my design consists of a medley of pictures of buildings, such as are of a well-known character and striking appearance, printed or otherwise placed upon the paper. Wrapping-paper and paper bags made from such paper 15 have a distinctive, novel, and attractive ap-

pearance, which is well calculated to interest and please the purchaser of the goods enclosed thereby.

What I claim is—

The design for wrapping-paper and paper 20 bags, which consists of a medley group of pictures of buildings, substantially as set forth.

In witness whereof I have hereunto set my hand and seal, at Indianapolis, Indiana, this 4th day of December, A. D. 1890.
